UNITED STATES PATENT OFFICE.

JOSEPH LAUFERTY, OF NEW YORK, N. Y.

SUSPENDER-END.

SPECIFICATION forming part of Letters Patent No. 255,175, dated March 21, 1882.

Application filed August 30, 1881. (No model.)

To all whom it may concern:

Be it known that I, JOSEPH LAUFERTY, a citizen of the United States, residing at New York, in the county and State of New York, have invented a new and useful Improvement 5 in Suspender-Ends, of which the following is a full, clear, and exact specification, reference being had to the annexed drawings.

My invention relates to an improvement in 10 suspender-ends; and the principal features of the invention are hereinafter more fully described, but more particularly pointed out in the claims.

Reference being had to the drawings, Figure 15 I shows my suspender-end attached to the tip. Fig. II, shows the material shaped to form my suspender-end.

Similar letters refer to similar parts throughout the drawings.

20 In the drawings, A represents the tip to which my suspender-ends are attached. B are my suspender-ends. D is the button-loop in my suspender-end.

In my invention, in order to make the suspender-ends B, I take a piece of leather, cloth, or other suitable material of about double the 25 length of the suspender-end, whose width varies from an inch and a quarter to an inch and a half, and paste on it a narrow strip of cloth, (indicated in Fig. II by H,) which, however, is not necessary, but may be used, if desired. Having 30 done this, I turn over sidewise both edges of the material toward the middle until one portion of the material overlaps the other, and then paste them together. I lay off a certain 35 portion of this strip of material at about an equal distance from each end, which is shown in Fig. II by the letters c c, and twist or fold, as the case may be, one edge of this intermediate portion, c c, round the other, having bent it outwardly, as shown in Fig. II of the drawings, leaving untouched the flat parts d and d'. These edges c c are sewed together as folded; 40 but when twisted of course no sewing will be required. To complete the suspender-end, I take one part, d', and turn it around and place

it on the top of the part d in such a manner that the intermediate part, c c, already sewed and folded or twisted, will assume the shape of the loop D, which is shown in Fig. I. The 50 flat parts d and d' are then sewed tightly together.

By making a suspender-end of leather or cloth in the manner described I am provided with a button-loop which is safe and strong 55 and capable of resisting, more satisfactorily than other button-loops the strain which is brought to bear upon it.

The suspender-ends, together with the tip, I embellish with appropriate figures or emblems, 60 which are partly shown in Fig. I; or they may be left plain.

I am well aware that there are various devices for suspender-ends; but none that I know of are made in the manner described.

65 What I claim, and desire to secure by Letters Patent, is—

1. The method hereinbefore more fully described and set forth of making suspender-ends for suspenders, which consists in taking 70 a rectangular-shaped piece of leather or other suitable material, as described, and folding one side over on the other, and then pasting them together, then in bending said piece of leather at or near the center, so as to form the part indicated by c c, and, lastly, in laying the parts d and d' of said piece of leather on top of each other and sewing them, so that in the operation the part c c shall form the button-loop 75 of the suspender-end.

80 2. The suspender-end B, composed of one continuous piece of leather or other material, arranged as described, having at either end the parts indicated by d and d' and in the middle the arc-shaped portion c c, adjusted and arranged in the manner described, and for the purposes set forth.

JOSEPH LAUFERTY.
